UNITED STATES PATENT OFFICE.

DAVID JOHN SCOTT, OF PLAINFIELD, NEW JERSEY, ASSIGNOR TO ISABELLA SCOTT AND DAVID J. SCOTT, EXECUTORS OF WALTER SCOTT, DECEASED.

OFFSET WEB-PERFECTING MACHINE.

1,311,138.

Specification of Letters Patent. Patented July 22, 1919.

Application filed September 29, 1916. Serial No. 122,839.

To all whom it may concern:

Be it known that I, DAVID J. SCOTT, a citizen of the United States, and a resident of Plainfield, in the county of Union and State of New Jersey, have invented certain new and useful Improvements in Offset Web-Perfecting Machines, of which the following is a specification.

The present invention relates generally to offset web perfecting machines and has more particularly reference to the general arrangement of the units and of the parts composing the same.

The main object of this invention is to produce a machine that will print and perfect paper by the offset method without the omission of parts essential to high grade results; and further, to render the parts composing the machine readily accessible for manipulation by the operator.

Accordingly, the invention consists of the features of construction, combination of parts and arrangement of elements, herein-after described, several preferred forms of which are disclosed in the accompanying drawings. However changes may be made in the particular construction herein disclosed without departing from the legitimate and intended scope of the invention.

In the drawings:

Figure 1 is a view in elevation, largely diagrammatic in form, of a machine embodying the invention.

Fig. 2 is a plan view, also largely diagrammatic, and partly in section, on the line 2-2 of Fig. 1, with the printing units removed but with the angle bars shown in their relative position to indicate the lead of the paper.

Fig. 3 is a view similar to Fig. 1, showing a modified form of the invention in which the paper is printed in several colors.

A indicates a form-carrying member, C a transfer or blanket member and E an impression member, constituting one unit, and B indicates a form-carrying member, D a transfer or blanket member and F an impression member constituting a second unit. The form-carrying and transfer members of each unit are arranged one above the other and the impression member out of line with the other members to form an exposed operating side, the two units being grouped with their operating sides outermost and

with the impression members innermost. The usual inking apparatus O is used in connection with each form carrying member; and, should the character of work require it, dampening mechanism, such as N, are employed for dampening the form. Said dampening mechanisms are located adjacent to the operating sides of the machine. In connection with the impression member of the second couple there is also provided an anti-smutting device 37 located on the upper surface of said impression member and intermediate the two units. Suitable throw-offs for the cylinders are provided so as to render the parts accessible. The transfer members are provided with sliding boxes and a handle 100 for controlling the boxes and by which they may be moved out of contact with the impression members and the form-carrying members by a movement outwardly from the operating sides of the machine. Similarly, the impression members are provided with sliding boxes or handles 101 whereby they may be thrown off the transfer members and moved inwardly of the machine toward each other. The dampening mechanisms N and the anti-smutting device 37 may be moved away from the members with which they engage by operating handles 102 controlling the sliding movement of the parts. A source I of the supply of paper is located beneath the units and, in the present instance, there may be two such sources from either of which the web may be led to a guide roller X and thence to the first unit of the machine. The source of supply is mounted in bearings I' which open outwardly from the outwardly operating sides of the machine so that the paper may be replenished with facility, the usual two rolls permitting the operator to operate the machine with one roll while the other roll is being replenished. L indicates a folder located at the end of the units and spaced therefrom to provide a suitable gangway or platform H; and preferably, above the first unit are arranged two angle bars 103, that are in line with folder L and that serve to bring the slitted sections of the web into superposed relation so that they may be directed to the folder. A slitter 104 and a straight bar 105 are located above the units and intermediate thereof. Located between the folder and the end of the units is a motor 106 which actu-

ates a gear 107 that drives the members of the printing units and which also actuates another gear 108 that drives folder L.

The paper is led from the source I of the 5 supply over guide roller X, thence between impression member E and transfer member C of the first printing unit, thence to the under side of impression member F and between the latter and the transfer member D 10 of the second unit, and thence upwardly to slitter 104, bar 105, and then the slitted sections are passed over angle bars 103, each being given a quarter turn to superimpose the same, after which the paper runs straight 15 to folder L.

In Fig. 3 is shown a modified form of the invention in which the two units, the folding mechanism, the angle bars and the slitter, etc., are arranged exactly as before.

20 In this instance, however, another unit is added consisting of form-carrying member B', transfer member D' and impression member F', and having the inking mechanism O and the dampening mechanism N, 25 as before, and also an anti-smutting device 37'. This unit is located under the second unit with its operating side outermost.

In this form of the invention the paper is led from the source of supply I over 30 guide roll X' to impression member E of the first unit, thence over guide roll X² downwardly of the machine between the units to guide roller X³, and thence upwardly between impression member F' and 35 impression member D' and between the same, and thence upwardly between impression member F and transfer member D of the second of the two first printing couples. Thence the paper rises upwardly be- 40 tween the units and passes to the slitter, angle bars and folder as before. In this case the paper is first printed on one side in a single color and is then printed on the other side in two colors, there being a sepa- 45 rate unit consisting of a form carrying, a transfer and an impression member for each color; and each of the impression members of the two superposed units are provided with anti-smutting devices to prevent the 50 previously printed side from soiling the surface of the impression members.

What is claimed, is:

1. A rotary offset web perfecting machine comprising: a plurality of units printing 55 from positive forms on opposite sides of impression receiving material, each unit including a form-carrying, a transfer and an impression cylinder all of substantially the same diameter, the form-carrying and trans- 60 fer cylinders arranged one above the other and the impression cylinder out of line with the other cylinders to form an exposed operating side, said units grouped with their operating sides outermost, and delivery 65 means located at the end of the units and

spaced therefrom to afford unobstructed access to said units, said means including a folder, a slitter and angle bars for giving both sections a single quarter turn to bring them in superposed relation to the folder. 70

2. A rotary offset web perfecting machine comprising: a plurality of units printing from positive forms on opposite sides of impression receiving material, each unit including a form-carrying, a transfer and an 75 impression cylinder all of substantially the same diameter, the form-carrying and transfer cylinders arranged one above the other and the impression cylinder out of line with the other cylinders to form an exposed operating side, said units grouped with their operating sides outermost, delivery means located at the end of the units and spaced therefrom to afford unobstructed access to said units, said means including a folder, a 80 slitter and angle bars for giving both sections a single quarter turn to bring them in superposed relation to the folder, and a source of supply of impression receiving material located beneath the units. 90

3. A rotary offset web perfecting machine comprising: a plurality of units printing from positive forms on opposite sides of impression receiving material, each unit including a form-carrying, a transfer and an 95 impression cylinder all of substantially the same diameter, the form-carrying and transfer cylinders arranged one above the other and the impression cylinder out of line with the other cylinders to form an exposed operating side, said units grouped with their operating sides outermost, delivery means located at the end of the units and spaced therefrom to afford unobstructed access to said units, said means including a folder, a 100 slitter and angle bars for giving both sections a single quarter turn to bring them in superposed relation to the folder, and an anti-smutting device located above the impression cylinder of the second unit and in 105 engagement with the surface thereof. 110

4. An offset web perfecting machine comprising: a plurality of units, each unit including a form-carrying, a transfer and an impression member, the form-carrying and transfer members being arranged one above the other and the impression member out of line with the other members to form an exposed operating side, the units being grouped with their operating sides outermost, a folder located at the end of the units and spaced therefrom to provide a gangway, a motor located between the end of the units and the folder, and driving connections from said motor for actuating the members of the 115 units and the folder. 120

5. An offset web perfecting machine comprising: a plurality of units, each unit including a form-carrying, a transfer and an impression cylinder, the form-carrying and 130

transfer cylinders being arranged one above the other and the impression cylinder out of line with the other cylinders to form an exposed operating side, the units being grouped 5 with their operating sides outermost, a folder located at the end of the units and spaced therefrom to provide a gangway, a motor located between the end of the units and the folder, and driving connections from said

motor for actuating the cylinders of the 10 units and the folder.

Signed at Plainfield, in the county of Union and State of New Jersey, this 27th day of September, A. D. 1916.

DAVID JOHN SCOTT.

Witnesses:

CARL E. DRANGE,
J. V. COLES.

It is hereby certified that in Letters Patent No. 1,311,138, granted July 22, 1919, upon the application of David John Scott, of Plainfield, New Jersey, for an improvement in "Offset Web-Perfecting Machines," an error appears in the printed specification requiring correction as follows: Page 1, line 92, strike out the word "outwardly"; and that the said Letters Patent should be read with this correction therein that the same may conform to the record of the case in the Patent Office.

Signed and sealed this 30th day of September, A. D., 1919.
